SNOW SCOOP

Cecil H. Cook, Youngstown, Ohio

Application March 6, 1956, Serial No. 40,477

Term of patent 7 years

(Cl. D35—2)

Figure 1 is a perspective view of the snow scoop, showing my new design;

Figure 2 is a side view thereof; and

Figure 3 is a bottom view.

The other side of the snow scoop, not shown, is a duplicate of the side illustrated.

I claim:

The ornamental design for a snow scoop, as shown and described.
